CONDENSER APPARATUS

Alexander I. Ponomareff, Havertown, Pa., assignor to Westinghouse Electric Corporation, East Pittsburgh, Pa., a corporation of Pennsylvania

Application September 26, 1947, Serial No. 776,359

1 Claim. (Cl. 257—26)

1

The invention relates to marine condensers and it has for an object to provide an improved circulating water scoop system therefor.

A more particular object of the invention is to provide an inlet scoop construction taking the place of the usual scoop, conduit, and inlet water-box arrangement and having a passage which diverges from its inlet end at the surface of the ship to its outlet end disposed adjacent to the condenser inlet tube plate.

Another object of the invention is to provide inlet scoop and overboard discharge structures connected to the ends of a surface condenser shell and wherein the structures and the shell are each of a section conforming to the outline shape of the tube plate or tube bank throughout with the inlet scoop structure having a passage which diverges from the inlet end thereof to its outlet end adjacent to the inlet tube plate and the overboard discharge structure has a passage which converges from its inlet adjacent to the outlet tube plate to its outlet at the surface of the ship.

A scoop-circulating system uses the relative velocity between the ship and the boundary layer to force water through the condenser tubes, and the objective is, of course, to provide a maximum head for this purpose with the least possible disturbance past the ship. In accordance with the present invention, to provide the minimum flow area, the throat or inlet area of the scoop passage is proportioned to pass the required quantity of circulating water at a mean velocity corresponding to the water velocity relative to the ship in the affected portions of the boundary layer. Assuming the ship's speed to be 40 knots, the mean velocity through the throat area of the scoop passage may be about 45 feet per second; and, to obtain the maximum quantity of water flowing through the condenser tubes, the scoop passage beyond the throat, and including the water box or discharge portion thereof, must be proportioned for uniform reduction of water velocity from 45 feet per second at the throat to the order of two or three feet per second at the tube entrance. To produce this large reduction in water velocity in a relatively short distance without undue turbulence or eddying, sudden changes in area at the inlet to the condenser, or along the scoop passage, should be avoided. The improved scoop, therefore, has a passage whose flow area gradually increases from the inlet to the outlet at the inlet tube sheet, and the passage is preferably of a cross section consistent with the geometrical shape of the

2

tube plate throughout its length, for example, rectangular. Losses are further minimized by having the discharge water box formed as a converging nozzle passage proportioned to produce uniform velocity distribution in the water being discharged overboard. In addition to rectangular formation of the scoop, to provide for a minimum height in marine practice consistent with location of water line, the condenser itself is preferably of rectangular section, and the overboard discharge nozzle passage is also preferably rectangular. Therefore, not only do the flow areas gradually increase and gradually decrease, but there is no transition from rectangular to circular flow areas and vice versa, in consequence of which the entering velocity is gradually transformed into pressure and pressure is gradually transformed into velocity without disturbance due either to sudden changes in area or to transition from rectangular to circular areas or vice versa.

In a marine plant, wherein each propeller shaft is driven by a high-pressure and a low-pressure turbine disposed side-by-side, a condenser for each power-developing unit may be arranged athwartship to save space and to provide for tube removal. As the present invention contemplates this arrangement of condenser, not only must the scoop be of rectangular section and gradually increasing in flow area, but, from the inlet, it must extend upwardly and rearwardly and be curved outwardly athwartship in a gradual manner so as to minimize turning losses.

Furthermore, in accordance with the present invention, the scoop, the condenser shell, and the overboard discharge conduit are fabricated from plate material; and, in this connection, the body of the scoop is comprised by four plates which taper in width so that, when they are joined at their edges, they provide a passage of suitable divergence. Three of the plates are curved by rolling and the remaining plate is warped so that when the plates are joined the passage extends upwardly and rearwardly and is curved outwardly.

Accordingly, a further object of the invention is to provide an inlet scoop structure having a passage which gradually increases in flow area from the inlet to the outlet arranged adjacent to one of the tube sheets.

Another object of the invention is to provide an inlet scoop, a surface condenser, and an overboard discharge conduit, each of rectangular section to avoid changes from rectangular to circular areas or vice versa and wherein the

passage of the scoop gradually increases in flow area from its inlet to its outlet.

A further object of the invention is to provide a marine condenser with means for circulating water therethrough and including a scoop structure having a passage which diverges from the inlet to the outlet adjacent to the inlet-end tube sheet and which extends rearwardly and upwardly and is curved outwardly to aline its outlet with the tube sheet.

The foregoing and other objects are effected by the invention as will be apparent from the following description and claims taken in connection with the accompanying drawings, forming a part of this application, in which:

Figure 1 is a plan or outline view showing a pair of condensers for a marine propulsion plant wherein each condenser is provided with the improved water-circulating means;

Figure 2 is an athwartship section showing one of the improved condenser arrangements;

Figure 3 is an isometric diagrammatic view of the improved condenser and inlet scoop and overboard discharge structures;

Figure 4 is a sectional view taken along the line IV—IV of Figure 2;

Figure 5 is a diagrammatic fragmentary view showing parts in section, the section of the scoop inlet portion being taken along the line V—V of Figures 1 and 2; and

Figure 6 is a perspective view of the scoop body portion.

In Figure 1, a pair of power-developing units 10, 10 drive the propeller shafts 11, 11. Each power-developing unit or installation comprises a high-pressure turbine 12 and a low-pressure turbine 14, both of which are connected, through reduction gearing, at 15, to the associated propeller shaft 11. Each unit or installation also includes a surface condenser 17 for the low-pressure turbine exhaust. The present invention is concerned more particularly with the condenser and the means for circulating water therethrough.

The condensers 17 are arranged athwartship underneath the turbines; and, as one installation is positioned forwardly of the other, adequate space exists for tube removal and accommodation of the circulating-water equipment.

Each condenser 17 includes a shell 18 encompassing tubes 19 whose ends are attached to the inlet and outlet tube sheets 20 and 21 carried by the ends of the shell, the inlet tube sheet 20 being disposed at the inboard end of the condenser. An inlet scoop structure, at 23, supplies water for flow through the tubes and an overboard discharge structure, at 24, provides for water issuing from the tubes being discharged overboard.

The scoop structure, at 23, includes an inlet or scoop portion 25 connected by an expansion joint 26 to a body portion 27 having a flange 28 engaging the adjacent tube sheet 20 to clamp the latter in place with respect to the shell in the same manner as is done by means of the conventional water box. A shut-off valve 29 and a check valve 30 are arranged between the inlet portion 25 and the body portion 27, the check or non-return valve being arranged to close against reverse flow. As shown in Figure 5, the scoop inlet section extends through the inner and outer walls 35 and 36 of the hull structure, the inlet end portion of such section being inclined at a suitably small angle with respect to the outer wall so as to provide an elongated inlet opening 37 flush with the bottom surface of the ship. A strainer plate

38 is located at the inlet opening and a splitter vane 39 having one end attached to the strainer plate extends lengthwise of the inlet portion. To promote the easy ingress of water with a minimum of turbulence and without the use of structure extending out from the surface of the ship, the rear wall 40 of the inlet section 25 is joined to the hull outer wall 36 by a rounded junction portion 41 and the front wall 42 is curved at 43 so as to be in tangent relation to the hull outer wall.

The overboard discharge structure, at 24, includes a body portion 44 connected through an expansion joint 45 and a shut-off valve 46 to the discharge portion 47.

The scoop structure has a passage 48 which diverges from its throat 49 at its inlet to its outlet end 50 adjacent to the inboard tube sheet 20. The scoop structure extends upwardly and rearwardly from its inlet end and is curved outwardly to aline its outlet end with the inboard tube sheet.

As the scoop passage diverges in the direction of flow and has its outlet end conforming to the adjacent tube sheet, there are no sudden changes or transitions in area resulting in eddies or losses. Further, as the passage is gradually curved to bring the outlet end into alinement with the adjacent tube sheet, sharp bends are avoided, and this, coupled with avoidance of sudden area changes, result in a passage conducive to effective flow with uniform pressure distribution and the absence of dead spaces.

The inlet scoop and the overboard discharge structures, as well as the shell, are all of rectangular section, in consequence of which not only does the construction as a whole lend itself readily to fabrication but, as transition from a circular section to a rectangular section or vice versa is avoided, energy losses and eddying are further reduced; and, in this connection, the nest of tubes is of rectangular transverse formation and the rectangular outlet end of the inlet scoop passage conforms to the tube grouping at the adjacent tube sheet.

The inlet scoop and the overboard discharge structures are each fabricated from plate material to provide an inlet scoop passage of gradually increasing flow area and an overboard discharge passage of gradually decreasing flow area to secure uniform velocity distribution. The inlet scoop body section 27 is fabricated from four plates 52, 53, 54 and 55 which taper in width to provide, when joined, for the requisite divergency. The plates 52, 53 and 54 are rolled to the required curvature and the plate 55 is warped so that when the plates are joined at the corners, there will result an inlet scoop structure which extends upwardly and rearwardly and is curved outwardly to bring its passage outlet into alinement with the inboard tube sheet. Likewise, the overboard discharge passage body portion 24 is formed by four curved plates 56, which are tapered outwardly and are joined at the corners to define an overboard discharge passage constituting a well proportioned converging nozzle which will produce uniform velocity distribution at the diffusing section 47.

From the foregoing, it will be apparent that the replacement of the conventional water boxes at the ends of the shell by inlet scoop and overboard discharge structures provide inlet and outlet passages which, respectively, diverge from the surface of the ship to the inlet end of the condenser without sudden area changes and con-

verge from the outlet end of the latter to the surface of the ship without sudden area changes, whereby more effective flow conditions are secured. Avoidance of turbulence or eddying is furthermore minimized due to the fact that the inlet scoop structure, the condenser shell, and the outlet scoop structure are all of rectangular section, whereby transition from a circular to a rectangular area or vice versa is avoided. These features provide for more effective and efficient circulation with the result that a given circulation is made possible with a scoop structure inlet section having a minimum throat area, thereby reducing to a minimum modification of the ship's structure required for accommodation of the scoop.

While the invention has been shown in but one form, it will be obvious to those skilled in the art that it is not so limited, but is susceptible of various changes and modifications without departing from the spirit thereof.

What is claimed is:

In a propulsion plant for a ship, a surface condenser and extending athwartship; said surface condenser including a shell which is rectangular in cross section, rectangular inboard and outboard tube plates connected to the ends of the shell, and a rectangular nest of tubes carried by the tube plates; means for circulating water through the tubes including inlet scoop and overboard discharge structures; said inlet scoop struc-

ture having a passage of rectangular section and whose inlet end is open to the exterior of the ship at the bottom thereof and whose outlet end is adjacent to the inboard tube plate; said inlet scoop structure extending upwardly and rearwardly and curved outwardly to align the outlet of its passage with the inboard tube plate; said scoop passage having its flow area divergent from its throat at the inlet end to the outlet end thereof, whereby entering water may flow therethrough without encountering sudden enlargements in flow area to provide for gradual transformation of velocity energy thereof into pressure energy from the inlet to the outlet ends; said inlet scoop structure including four plates which taper in width and have their edges joined to form the diverging rectangular scoop passage and three of said plates having rolled curvature and the remaining plate being warped so that joining thereof at their edges results in a passage which extends upwardly and rearwardly and is curved outwardly.
